SUBMERGIBLE DRILLING BARGE

John T. Hayward, Tulsa, Okla.

Application September 17, 1949, Serial No. 116,327

2 Claims. (Cl. 61—46)

1

This invention relates to improvements in drilling barges, particularly to barges of the submergible type which are adapted especially for use as drilling rig foundations in open ocean areas.

This application is a continuation-in-part of my copending U. S. application Serial No. 65,475, now Patent No. 2,551,375 issued May 1, 1951.

In the aforesaid co-pending application, a form of drilling barge is disclosed which is particularly adapted for submergence and raising by the "one-end-first" method, in order to assure complete and safe stability during the submergence and raising operations. The "one-end-first" method, as described in that application is one which, in effecting submergence of the barge hull, submergence is begun from one end of the hull, the opposite end being maintained in buoyant condition and extending above the water surface until the submerging end has come to rest on the water bottom, after which the extending end is submerged to bring the entire hull to rest on the bottom. A similar procedure is followed in raising the barge hull, that is, one end is first rendered buoyant and raised to the surface while the opposite end remains on bottom to maintain the hull in stable condition until the rising end has attained stabilizing buoyancy, and then the submerged end is rendered buoyant to again bring the entire structure to the fully floating position.

The present invention has for its principal objects the provision of an improved barge structure which is particularly adapted for submergence and raising by the one-end-first method; which may be employed with high degree of safety and stability in water depths exceeding the molded depth of the hull, as well as in water depths less than the molded depth of the hull; which is particularly compact and efficient in design; which may be constructed with considerably reduced quantities of material and at lower cost than earlier designs; and which has a high degree of stability both afloat and on bottom and during submergence and raising.

Other and more specific objects and advantages of this invention will become apparent from the following detailed description when read in conjunction with the accompanying drawings which illustrate useful embodiments in accordance with this invention.

The principles involved in the design of a submergible hull in accordance with this invention will be first described in connection with Figs. 1, 2 and 3 which are more or less diagrammatic illustrations in profile of a conventional hull shape and of several shapes and arrangements in ac-

2

cordance with several embodiments of this invention.

Barge hulls of the designs which are conventionally employed as drilling rig foundations for water drilling are ordinarily constructed in the form of rectangular box-like structures of generally uniform molded hull depth, having a generally flat bottom and a generally flat deck disposed in parallel relation to the bottom. When such hulls are submerged or raised using the one-end-first technique described in the aforesaid co-pending application, the end portion which is kept buoyant and remains afloat while the opposite end is being submerged will, due to the inclination of the hull, necessarily extend for a substantial distance above the water surface. Due to the generally rectangular shape of the conventional hull and the inclination of the latter during submergence and raising, the extending section will have a generally triangular shape in profile, the water surface from which it emerges forming the base and the apex being the upper corner of the hull. This condition is illustrated in Fig. 1 in which a profile of a conventional rectangular hull H is shown in broken lines in the normal fully afloat, and fully submerged positions with respect to a water surface W, and in solid lines showing the partially submerged inclined position at which one end of the hull is in contact with the land bottom L during submergence and raising. It will be seen that the triangular section ACB of the hull extends above water level W; the line AB indicating the water plane of the hull when in this position.

I have found that the stability of a submergible hull will be increased if the triangular section ACB is, in effect, sheared off. In fact, because the center of gravity of the section of the hull above the line A—B will be above the center of buoyancy of the submerged hull, the section ACB actually reduces the stability of the hull. By eliminating the section ACB, the center of gravity will be lowered, thereby increasing the stability and at the same time substantially reducing the total quantity of steel and other construction material and expense which would be required in the construction of a conventional rectangular hull of the same overall dimensions such as that illustrated in Fig. 1. Other advantages also result from this change in hull design, as will be pointed out more fully hereinafter.

Fig. 2 is a diagrammatic profile view of a hull in accordance with one embodiment of this invention wherein the section ACB of Fig. 1 has been removed and showing the thus-modified

hull in the several positions corresponding to those illustrated in Fig. 1. It will be seen that when the hull is in the fully afloat position, the rear portion having the now upwardly sloping deck D—D', will still provide substantial hull volume which will extend well above the water surface, thereby providing adequate stability in the floating position and during the several stages of submergence of the opposite end of the hull until the latter is in physical contact with land L, as shown in full lines in Fig. 2. In the latter position, it will be seen that the sloping portion D—D' of the deck has assumed a position substantially parallel to the water surface and only a very small rectangular section of the hull extends above the water surface. Since this section will be maintained in buoyant condition until the opposite end touches bottom, the hull remains fully stable and as soon as the submerged end lands on bottom, the direct contact between the hull and the bottom will stabilize the hull against any rolling movements, so that the buoyancy in the floating end no longer is important to maintain stability. It is only necessary to then destroy the buoyancy of the floating end to cause it to sink so as to bring the entire hull to the fully submerged position as illustrated.

The same stability control occurs during raising. The sheared or sloping end will be rendered buoyant to raise it while the other end is kept ballasted to hold it on bottom until the sloping end has risen to the surface and is buoyantly stable, whereupon the submerged end is deballasted to render it buoyant so that it will rise to the surface to thereby re-float the entire structure.

The angle at which the hull deck D—D' (and the associated portion of the hull) is sloped upwardly relative to a horizontal plane, such as the plane of the hull bottom, will be determined ordinarily by length of the hull and the depth of water in which it is designed to be operated. This angle may be made substantially equal to the angle of inclination of the hull when the opposite end is on bottom. These angles are indicated respectively at x and y in Fig. 2. When angles x and y are equal, it will be evident that deck portion D—D' will be substantially horizontal and parallel both to water surface W and land bottom L when the hull is in the inclined position shown in solid lines in Fig. 2. It will be understood, however, that considerable latitude may be exercised in determining the angle at which the end section of the hull is to be sloped.

In accordance with another embodiment of this invention, both end portions of the hull may be provided with the sloping or angular configuration previously described without materially affecting the stability of the hull during submergence or raising and thereby effecting additional savings in material and construction cost. Fig. 3 illustrates diagrammatically the profile of a hull in accordance with this embodiment, showing such a hull in the several positions corresponding to those illustrated in Fig. 2. In this embodiment it will be seen that the hull sections D—D' and D'—E slope upwardly from the opposite ends of the hull, joining at the point D' which is located generally in the midship portion of the hull, but not necessarily at the exact mid-point thereof, and may be off-set from the longitudinal mid-point of the hull, depending generally upon the loading in the opposite end portions of the hull and its general design.

Figs. 4, 5, 6, and 7 illustrate in greater detail

a design of submersible drilling barge structure embodying the above-described hull principles and conforming generally to the modification illustrated particularly in Fig. 3.

The hull H is a hollow, box-like structure, generally rectangular in plan, and is composed of a generally flat, horizontally disposed bottom 10, connected to upstanding side walls 11—11 and end walls 12—12. The upper edges of side walls 11—11 slope upwardly from their opposite ends to a juncture point, indicated at D', located at an intermediate point between the ends of the hull. A deck, composed of oppositely sloping portions 13—13, is laid over the sloping upper edges of side walls 11—11, having its side edges connected thereto and its end edges connected to the upper edges of end walls 12—12 to fully enclose the hull. One end of the hull, which will be designated as the bow for purpose of easier description is provided with an arcuate rake 14, curved about a relatively large radius, which serves, when in contact with the land underlying the water body in which the structure is operated, as a pivot about which the hull may rotate during raising and lowering by the "one-end-first" technique.

The hull is provided with a longitudinal slot 15 which extends inwardly of the hull from the bow generally along the longitudinal axis of the hull for a considerable portion of its length, to form the conventional drilling slot commonly provided in drilling barges.

The interior of the hull is divided by means of a plurality of bulkheads 17—17 into a suitable number of ballast compartments 18—18 of any desired sizes and arrangement. A compartment 19, located generally in the mid-ship portion of the hull and aft of the inner end of drilling slot 15, may be employed as a machinery space, engine room, pump room, or the like, in which suitable and generally conventional ballast-handling machinery particularly may be conveniently located.

A plurality of supporting columns 20 extend upwardly from the hull and are arranged thereon in a suitable longitudinally and laterally spaced pattern adapted to support on their upper ends a working platform 21 on which may be mounted the usual drilling derrick 22 and other drilling machinery, and on which may be mounted an enclosed housing 23, which may serve for crew quarters, machinery rooms and the like. The derrick 22 will be centered over the inner end of drilling slot 15 through which access is thus provided to the underlying land for the drilling tools operated from the derrick, and which provides means for withdrawing the structure from about the well when drilling is completed.

Supporting columns 20 may be of any suitable shape and arrangement and are preferably of hollow cylindrical shape, as a minimum number of cylindrical columns of appropriate cross-sectional area will provide adequate support strength for the platform load without requiring any cross-bracing, thereby decreasing the weight, complexity and cost of the platform-supporting structure and, at the same time, increasing to a maximum degree the wave-transparency of the platform-supporting structure. Such wave-transparency is an important consideration in employing barge structures of the type described for drilling in open ocean areas. The hollow bores of columns 20 may also be employed as communication trunks between platform 21 and the interior of the hull to provide means for access thereto by personnel when the hull is submerged and for

stringing water, fuel oil, power lines, and the like between the platform and the hull. Columns 20 will be made of such length as to extend well above the surface of the water body in which the hull is to be submerged when the hull bottom is resting on the underlying land. Platform 21 may thus be supported at a sufficient height above the water surface so that operations conducted therefrom will not be subjected to changes in water level by tides, waves and other water surface movements.

The drilling barge structure, constructed as above described, will be floated to a water location in any suitable and conventional manner, and will be fully stable while afloat. When the drilling location is reached, the hull will be submerged employing the "one-end-first" technique, described in my aforementioned application, Serial No. 65,475, to safely place the hull in position on the underlying land and as noted previously, the structure will be fully stable when the hull is submerged by that procedure. When drilling has been completed the structure may be refloated again using the "one-end-first" procedure with complete safety throughout the raising operation.

If desired, additional stabilization of the hull may be provided during the various operating stages by means of supplementary submergible hull sections or pontoons, which may be ranged along the sides of the hull, particularly along the portion which is last to be submerged and the first to be refloated. Such hull sections or pontoons may be constructed and operated in the manner disclosed in my co-pending application, Serial No. 44,626, filed August 17, 1948.

Submergible hulls in accordance with this invention possess a number of important advantages, in addition to those previously mentioned, over more conventional types of hulls when employed as submergible foundation for drilling rigs operating in open ocean areas. The novel shapes permit substantial reductions in the height dimensions of the major portions of the hull and this, in turn, permits the hull to be more readily braced internally and made much stronger so as to resist relatively high collapsing pressures. As a result hulls in accordance with this invention may be safely used in much deeper water than hulls of more conventional designs.

Moreover, hulls designed in accordance with this invention may also be used with safety in water depths shallower than the maximum molded depth of the hull. This provides a great degree of flexibility in employment of such hulls, particularly in open ocean areas where such structures are ordinarily subject to numerous and often widely changing water levels such as result from wave movements and changes in tide levels.

When the more conventional flat-decked hulls are submerged in water of insufficient depth to keep the hull fully submerged at all times, a portion will protrude above the water surface which

will have a relatively large water plane generally equal to the transverse area of the hull. As a result such hulls are subject to being raised off bottom by every passing wave or raise in tide, a condition which is extremely hazardous for drilling. On the other hand, with a hull designed in accordance with the present invention, as for example, the design illustrated in Fig. 4, the hull volume, which will extend above the water level, is much less than in the cases of conventional hulls. Moreover, due to the triangular profile of the hull, any rises in water level will be accompanied by a rapid reduction in the water plane and the tendency, therefore, of the hull to lift with each passing wave or tide rise will be greatly reduced. Furthermore, when used in shallow water, the sloping deck will greatly reduce the under-cutting action of waves breaking over the ends of the hull, thereby additionally contributing in an important respect to the safety of the drilling operations being conducted from the structure.

It will be understood that various alterations and changes may be made in the details of the illustrative embodiments of this invention within the scope of the appended claims but without departing from the spirit of this invention.

What I claim and desire to secure by Letters Patent is:

- 30 1. A submergible drilling barge, comprising, an enclosed generally rectangular hull having a substantially flat bottom, and having its upper side portions sloping upwardly from at least one end toward the mid-portion of the hull at an angle 35 to the bottom determined by the length of the hull and the depth of a water body in which it is submerged, said angle being such that the hull volume at said one end which extends above the surface of the water body when the opposite end 40 of the hull is resting on bottom approaches a minimum.
2. A drilling barge according to claim 1 wherein in the upper portion of said opposite end slopes upwardly toward said mid-portion at substantially 45 said angle.

JOHN T. HAYWARD.
